UNITED STATES PATENT OFFICE.

GEORGE W. MAXWELL, OF SAN FRANCISCO, CALIFORNIA.

MILK-CONTAINER.

No. 923,061.

Specification of Letters Patent.

Patented May 25, 1909.

Application filed December 5, 1905. Serial No. 290,423.

To all whom it may concern:

Be it known that I, GEORGE W. MAXWELL, citizen of the United States, residing at San Francisco, in the county of San Francisco and State of California, have invented certain new and useful Improvements in Milk-Containers, of which the following is a specification.

My invention relates to containing vessels 10 or receptacles and more particularly to such devices as are formed from fibrous material, preferably paper, and it has for its object to provide a vessel of this character that can be cheaply formed yet which will possess great 15 strength and can be hermetically sealed and thereby preserve its contents from contamination or decay.

An embodiment of the invention is shown in the accompanying drawing which shows a 20 central longitudinal section of the invention.

Referring more particularly to the drawing, 1 indicates the body of my containing vessel which is preferably of tubular form being shown in the drawings as the frustum of a cone. It is also preferably formed from fibrous material, as a single sheet or thickness of paper in the form of a segment of an 25 annular disk. In forming the body the blank is rolled into tubular form with its edges overlapped, and hermetically joined together, as by a line of glue or cement.

The bottom is permanently and preferably 30 hermetically secured to the lower or smaller end when the vessel is formed, and the top or cover is temporarily secured near the upper end when the vessel is filled.

The bottom is in the form of a disk as shown at 6, similar to the top 7, and inserted 40 into the interior of the body near the end. If desired, the bottom can be forced into the body with sufficient pressure to cause the body to bend or bulge out around the edge of the disk as shown at 9 which increases the 45 contact between the surfaces to make a tighter joint and also prevents the possibility of the bottom being forced back up into the larger diameter of the body and thereby loosening the joint and rendering it more 50 liable to leak and for the bottom to come out. The bottom is placed in position before the vessel is treated to a coating of liquid repelling material, as by being dipped into melted paraffin, which renders the material 55 of the vessel water proof and also hermetically closes the joint between the bottom and

the body, as well as the edges of the seam or joint from top to bottom of the body.

As above stated the top 7 is in the form of a flat disk of sufficient thickness to give the 60 requisite strength and rigidity to hold the contents against removal, even with rough usage, and its edge may be slightly beveled to more perfectly contact with the interior 65 of the body when inserted for retaining the contents. After the top has been inserted to the required distance, which may be far enough to slightly bend or bulge out the side of the body as shown at 10, it is immovably secured in place by a plurality of tongues or 70 inwardly extending projections 11 which are formed by three incisions 12, 12 and 13 through the wall of the body, two at the sides of the tongue, preferably parallel with each other, and one at the bottom, which 75 joins the other two. The bottom cut or incision is at a slight distance below the plane of the top of the cover as shown at 14, whereby, when the tongue is forced in, which is preferably done by machinery at the 80 time the vessel is filled, its lower edge will engage firmly with the cover and prevent any outward movement thereof, which would have a tendency to loosen the joint and thereby permit leakage or the entrance 85 of air. The insertion of the free end or lower edge of the tongue displaces a very small portion or thickness of the cover forming a shallow recess and thereby insures a 90 perfect contact between the two throughout the thickness of the tongue.

As above described my containing vessel can be so cheaply formed that it can be thrown away after once using, thereby rendering it possible to provide a receptacle for 95 perishable products which is absolutely clean and can be sterilized, as at the time of manufacture when it is dipped in heated paraffin for water proofing it. This renders it peculiarly adapted for milk as it can be filled at 100 the creamery or other milk depot while the milk is pure and fresh and, as the vessel is made by automatic machinery, and sterilized as above described, there is absolutely no 105 chance for it to become contaminated except while being handled preparatory to filling, when extra precautions can be taken to preserve it in its purity and cleanliness. And as it is to be thrown away, or not used, after having been emptied, its use saves all the 110 cost and waste of cleaning glass bottles besides avoiding the danger from imperfect

cleaning and lack of sterilization as it is impossible to heat a glass vessel to over 200 degrees, the sterilizing point, without taking a much longer time than will be given by the ordinary milk producer or dealer. The vessel can also be shipped as readily as glass with less cost for freight and, in being sold, each package is complete and can be handled as freely as any other article of like structure.

The vessel makes a very good drinking cup after the cover has been removed, thereby enabling the purchaser to use the contents directly from the vessel, if desired. And experience has shown that even with larger sizes, as I propose making three sizes for milk, the pint, half pint and quart, the filled vessel can be dropped upon the floor without breaking or spilling any of its contents. This arises from the great strength that can be secured by forming a sheet of paper into tubular form and rigidly securing thick circular disks in the ends thereof. The tongues by which the top or cover is secured in place, preferably by automatic machinery at the time the vessel is filled, are short and inclined from above and are in such firm contact with the cover at all times that it is almost impossible to remove the cover while they are in place, yet when it is desired to remove the cover the tongues can be easily and quickly forced back into the plane of the body, when

the cover can be removed in any desired manner and the contents removed or used, as from an ordinary vessel. Of course the vessel can be used for other products than milk, but I have found it so peculiarly adapted for containing milk that I propose using it more largely for that than for any other articles.

Having described my invention what I claim as new and desire to secure by Letters Patent, is:

A containing vessel made of paper and comprising a tapering body formed in one piece, a bottom disk permanently held in the smaller end of the body, a cover disk for the larger end thereof, and a plurality of tongues formed from the body and projecting inwardly and downwardly, the said tongues standing at an inclination to the body of the container and having their free ends extending below the upper surface of the cover disk and embedded in the body material thereof and wedging the said disk against the tapered sides of the vessel said tongues receiving the pressure from the cover in a direction longitudinally of themselves.

In testimony whereof I have affixed my signature, in presence of two witnesses, this 23rd day of November 1905.

GEORGE W. MAXWELL.
